UNITED STATES PATENT OFFICE

THOMAS W. B. WATLING, OF CHICAGO, ILLINOIS

DESIGN FOR A CASING FOR A WEIGHING SCALE

Application filed October 7, 1930. Serial No. 37,170. Term of patent 7 years.

To all whom it may concern:

Be it known that I, THOMAS W. B. WATLING, a citizen of the United States, residing in Chicago, county of Cook, and State of Illinois, have invented a new, original, and ornamental Design for Casing for a Weighing Scale, of which the following is a specification, reference being had to the accompanying drawing, forming a part thereof.

Fig. 1 is a front elevation of the casing for weighing scale showing my new design, and

Fig. 2 is a side elevation of the same.

I claim:

The ornamental design for a casing for a weighing scale, as shown.

THOMAS W. B. WATLING.
